UNITED STATES PATENT OFFICE.

EDWARD SCHWARTZ, OF NEW YORK, N. Y., ASSIGNOR TO MANHATTAN ELECTRICAL SUPPLY COMPANY INC., OF JERSEY CITY, NEW JERSEY, A CORPORATION OF MASSACHUSETTS.

DETACHABLE CONNECTOR.

1,359,280.

Specification of Letters Patent. Patented Nov. 16, 1920.

Application filed October 10, 1918. Serial No. 257,545.

To all whom it may concern:

Be it known that I, EDWARD SCHWARTZ, a citizen of the United States of America, residing in the city, county, and State of New York, have invented certain new and useful Improvements in Detachable Connectors, of which the following is a specification.

My invention relates to detachable connectors and particularly to a device for establishing electrical connection between the conductors of adjacent cable ends, the object of my invention being to provide an efficient device of economical construction having certain features of improvement hereinafter described or shown in the accompanying drawing, in which—

Figure 1 is a side elevation of a connector in which my invention is illustratively embodied;

20 Fig. 2 is an end elevation thereof;

Fig. 3 is a longitudinal section through the detached parts of the connector;

Figs. 4 and 5 are cross sections on the lines 4—4 and 5—5, Fig. 3, respectively;

25 Fig. 6 is a perspective of one of the plug terminals; and

Fig. 7 is a similar view, partly in section, of one of the receptacle terminals.

While certain features of the present invention are applicable to other forms of connectors, I have here shown my invention embodied in a device of the type designed to afford a detachable connection between the separable ends 10 and 11 of a cable, each comprising conductor wires 12 and 13. While the parts are reversible in position, the cable end 10 is here shown secured to the receptacle element A of the connector and the cable end 11 attached to the plug element B of the connector.

The receptacle element A comprises a button 14 of insulating material, centrally pierced at 15 by a rectangular hole to receive the jacks of the plug element hereinafter described. The opposite ends of the rectangular passage so formed are rabbeted to the shoulders 16 to accommodate the receptacle terminals, one of which is shown on an enlarged scale in Fig. 7. These terminals are identical in construction and each comprises a strap of sheet metal 17, the side margins of which are flanged at 18 to impart a channel section to the inner end of

the strap. The opposite end projects beyond the end of the button and is also provided with marginal flanges 19 extending in opposite direction from the flanges 18 and affording a channel section oppositely faced and tapped at 20 to receive the binding screw 21. The intermediate portion of the strap is shouldered at 22 to afford an offset, which is engaged by the incurved end 23 of the arm 24 of a spring loop which embraces the inner end of the terminal strap and presents its other arm 25 to the passage 15 as a spring brush contact. Offset from the outer end of one of the flanges 18 is a lug 26 tapped at 27 to receive a securing screw 28, by which the terminal is secured in position on the button 14. The button is shouldered at 29, and the nose so formed threaded at 30 to receive the screw cap 31, within the chamber 32 of which are confined the bared wire ends and taping of the cable 10.

The plug member of the connector comprises an insulating button 33, centrally pierced by a rectangular aperture substantially corresponding in diameter to the area and shape of the aperture 15 of the receptacle 75 14. At the opposite sides of this aperture are located terminal straps 34, each identical in construction and one of which is shown on a larger scale in Fig. 6. These straps are of sufficient length to project beyond opposite ends of the plug and have 80 marginal flanges 35 imparting a channel section thereto. In mounted position on the plug the channels thus formed face each other and form the jacks of the plug. At the opposite end of the button, each strap has offset flanges 36 faced in the opposite direction from the flanges 35 and forming a channel section tapped at 37 to receive the binding screw 38. A lug 39, offset from the end of one of the flanges 35, is tapped at 40 95 to receive the holding screw 41, by which the strap is secured upon the button 33. In order to hold the straps 34 rigidly in position and to prevent their deformation, I interpose between the same a block of insulation 42 which is forced into position between the channels 35 with sufficient frictional engagement to maintain it in position without other securing means. The button 33 is shouldered at 43 and its nose tapped at 44 100 to receive the cap 45, which screws thereon

and houses, in like manner as the cap 31, the connections between the wires 12 and 13 of the cable end 11 and the respective binding screws 38.

- 5 The operation of the device is obvious. Having wired the two members of the connector, it is merely necessary to insert the plug 13 into the receptacle A. The size of the channels 34 is such that they sleeve into 10 the channels 18 with approximate exactness, and the frictional engagement thus established is reinforced by the pressure of the brushes 25 carried by the receptacle terminals. To open the circuit, it is only necessary to withdraw the plug.

The construction shown is one of great economy, since the insulation parts are readily molded from insulating composition, and the metal parts are readily struck from 20 sheet metal and formed to shape in dies. The assembly of the metal parts on their respective buttons is an extremely simple operation, while the completed device affords a very efficient, rugged connector, not likely 25 to be injured by careless handling.

Various modifications in detail of construction will readily occur to those skilled in the art without departing from what I claim as my invention.

30 I claim:

1. In a detachable connector, a plug member comprising a centrally pierced insulating button, a pair of spaced conducting straps passing through said piercing and 35 projecting from the opposite ends of said button, binding screws tapped into said straps beyond one end of said button, and an independent spacing block of insulation frictionally engaged between the ends of 40 said straps projecting beyond the opposite end of said button.

2. The combination with a construction such as that recited in claim 1, of means for holding said straps securely on said button.

- 45 3. In a construction such as specified in claim 1, straps of channel section faced toward each other to receive and confine said spacing block.

4. In a construction such as specified in 50 claim 1, straps of opposite channel section at their opposite ends projecting beyond the insulating button.

5. In a construction such as specified in 55 claim 1, straps of channel section faced toward each other at one end and confining

the spacing block therebetween and of opposite channel section at the opposite end of the plug, together with binding screws tapped into said straps at the latter end thereof.

6. In a detachable connector, a socket member comprising an insulating button centrally pierced by a shouldered passage rabbeted at opposite sides thereof, a pair of spaced conducting straps engaged in said rabbet and projecting beyond one end of the button, binding screws tapped into said projecting ends of the straps, and spring brush contacts embracing said straps and projecting into the receptacle passage.

7. In a construction such as specified in claim 6, a lug on each strap and means piercing the button and engaging said lug to hold the strap in position.

8. In a detachable connector, an insulating button and a terminal strap carried thereby, an offset shoulder on said strap and a spring contact brush loop embracing said strap and having one end offset to engage said shoulder in adjusted position and 75 its other end facing the opposite side of the strap to afford a spring brush engagement with a coöperating plug.

9. In a detachable connector, an insulating button recessed to form a receptacle 85 chamber and having channel terminals faced toward each other in said chamber and extending substantially parallel in the direction of their length, and a coöperating jack having substantially parallel channel terminals embraced within the terminals of the receptacle on the straight inward thrust of the jack into the receptacle chamber.

10. In a detachable connector, an insulating button recessed to afford a receptacle chamber, channel terminals faced toward each other in said chamber, and spring brush contacts overlying the opposed faces of said terminals, in combination with a co- 95 operating jack having substantially parallel channel terminals engaging said brush contacts and embraced within the channel terminals of the receptacle on the straight inward thrust of the jack into the receptacle 100 chamber.

In testimony whereof I have signed my name to this specification.

EDW. SCHWARTZ.
